UNITED STATES PATENT OFFICE.

LOUIS DANIEL VANNEY, OF FINCHLEY, LONDON, ENGLAND.

MEANS FOR SECURING LOCKS.

Application filed June 18, 1923. Serial No. 646,208.

To all whom it may concern:

Be it known that I, LOUIS DANIEL VANNEY, subject of the King of Great Britain and Ireland, and residing at Lichfield, Hendon Lane, Church End, Finchley, London, England, have invented new and useful Means for Securing Locks, of which the following is a specification.

My invention relates to an improved method of securing locks and the like in pianoforte cases, drawers, and other fine cabinet work where it is desired to obtain a neat smooth finish.

According to the present invention the lock or latch plate or the equivalent thereof is provided with means upon the surface normally concealed when the lock or latch plate is in position whereby either may be held in position.

In order that my invention may be clearly understood and readily carried into effect, I have appended hereto one sheet of drawings illustrating same, in which:—

Fig. 1 is a fragmentary view in section of the keyboard base and cover of a piano illustrating the application of my invention.

Fig. 2 is a side elevational view illustrating the combined lock with securing screws detached, the jamb or latch plate being shown in section.

Fig. 3 is a plan view of Fig. 2.

Figs. 4 and 5 are sectional side elevation and inverted plan views respectively of the lock casing.

Referring to the drawings which illustrate the preferred embodiment of my invention, the lock casing 1 is closed at its lower end by bending over one or both of the side plates 2 to provide a base 3 upon the upper or inner face of which is slidably mounted a securing plate 4 having a screw threaded hole therein adapted to receive a screw 5 passed upwards through the baseboard 6, so that the action of threading the screw 5 into the hole will have the effect of drawing the upper plate 7 tightly into the recess prepared for it in the top of the baseboard 6. The base 3 of the lock is formed with an aperture 8 to allow the screw 5 to pass therethrough into the plate 4, such aperture being sufficiently large to allow the plate 4 to be moved endwise to a sufficient extent to provide a certain amount of latitude with regard to the location of the screw by which the lock is held in position.

The upper plate of the lock is recessed in the woodwork so as to lie flush therewith in the usual manner, but owing to the aforementioned method of fitting no screw holes are required and in order to facilitate fitting, I prefer to radius off the ends of this plate to a semi-circular shape. This will enable the plate to be accurately fitted by cutting the ends of the recess with a suitable bit or rotary cutter of the requisite size.

The latch plate 9 is preferably secured in position in a somewhat similar manner, its top plate 10 being recessed as described in the preceding paragraph with regard to the lock. The hole 11 for the reception of the retaining screw 12 in this case being located in a substantially U-shaped member 13. The U-shaped member has its ends secured by riveting, soldering or other suitable manner to the back of the latch plate. Where riveting is employed the heads of the rivets will be finished off flush with the top surface of the plate 10, the whole surface subsequently preferably being lacquered over.

In a method of fitting locks and latch plates according to my invention, the method of securing them in position is entirely concealed, and no objectionable screw heads are exposed, thus enabling a very clean and smooth finish to be obtained. It is also possible to remove the lock or latch plate without damaging the exposed portions as will almost certainly occur in removing old screws. No crevices are exposed which tend to collect dirt or polish and thus mar the effect of fine cabinet work.

I claim:—

1. Means for securing locks, comprising a lock plate, a securing plate having at least one threaded hole associated with the concealed portion of the lock plate, at least one screw adapted to be screwed into its threaded hole from the back of the part in which the lock is located and a plain flange to the face of the lock adapted to be clamped into a recess in the part when the screw is tightened.

2. Means for securing locks comprising a lock plate, side plates, a securing plate having at least one threaded hole associated with the concealed portion of the lock plate, turned over edges to the side plates of the lock with which the securing plate is slidably engaged, these turned over edges being cut away to permit movement of the plate

without obstructing the threaded hole therein, at least one screw adapted to be screwed into its threaded hole from the back of the part in which the lock is located and a plain flange to the face of the lock adapted to be clamped into a recess in the part when the screw is tightened.

3. Means for securing locks comprising a lock plate, a securing plate having at least one threaded hole associated with the concealed portion of the lock plate, at least one screw adapted to be screwed into its threaded hole from the back of the part in which the lock is located, a plain flange to the face of the lock adapted to be clamped into a recess in the part when the screw is tightened, and semi-circular ends to the flange to fit a recess whose ends are cut by drilling with a suitable bit.

20 4. Means for securing locks comprising a lock plate, side plates, a securing plate having at least one threaded hole associated with the concealed portion of the lock plate, turned over edges to the side plates of the lock with which the securing plate is slidably engaged, these turned over edges being cut away to permit movement of the plate without obstructing the threaded hole therein, at least one screw adapted to be screwed into its threaded hole from the back of the part in which the lock is located, a plain flange to the face of the lock adapted to be clamped into a recess in the part when the screw is tightened, semi-circular ends to the flange to fit a recess whose ends are cut by drilling with a suitable bit.

25 5. Means for securing locks comprising a lock plate, a securing plate having at least one threaded hole associated with the concealed portion of the lock plate, at least one screw adapted to be screwed into its threaded hole from the back of the part in which the lock is located, a plain flange to the face of the lock adapted to be clamped into a recess in the part when the screw is tightened, a latch plate for the reception of the bolt of the lock, a bent strip secured to the back of this latch plate and having at least one hole for at least one concealed screw for securing it in place.

30 6. Means for securing locks comprising a lock plate, side plates, a securing plate having at least one threaded hole associated with the concealed portion of the lock plate,

55 turned over edges to the side plates of the lock with which the securing plate is slidably engaged, these turned over edges being cut away to permit movement of the plate without obstructing the threaded hole therein, at least one screw adapted to be screwed into its threaded hole from the back of the part in which the lock is located, a plain flange to the face of the lock adapted to be clamped into a recess in the part when the screw is tightened, a latch plate for the reception of the bolt of the lock, a bent strip secured to the back of this latch plate and having at least one hole for at least one concealed screw for securing it in place.

60 7. Means for securing locks comprising a lock plate, a securing plate having at least one threaded hole associated with the concealed portion of the lock plate, at least one screw adapted to be screwed into its threaded hole from the back of the part in which the lock is located, a plain flange to the face of the lock adapted to be clamped into a recess in the part when the screw is tightened, semi-circular ends to the flange to fit a recess whose ends are cut by drilling with a suitable bit, a latch plate for the reception of the bolt of the lock, a bent strip secured to the back of this latch plate and having at least one hole for at least one concealed screw for securing it in place.

65 8. Means for securing locks comprising a lock plate, side plates, a securing plate having at least one threaded hole associated with the concealed portion of the lock plate, turned over edges to the side plates of the lock with which the securing plate is slidably engaged, these turned over edges being cut away to permit movement of the plate without obstructing the threaded hole therein, at least one screw adapted to be screwed into its threaded hole from the back of the part in which the lock is located, a plain flange to the face of the lock adapted to be clamped into a recess in the part when the screw is tightened, semi-circular ends to the flange to fit a recess whose ends are cut by drilling with a suitable bit, a latch plate for the reception of the bolt of the lock, a bent strip secured to the back of this latch plate and having at least one hole for at least one concealed screw for securing it in place.

70 LOUIS DANIEL VANNEY.
